UNITED STATES PATENT OFFICE

2,376,290

SERVICING IMPLEMENT FOR BEACONS

George F. Stewart, Winchester, Mass.

Application February 2, 1944, Serial No. 520,740

1 Claim. (Cl. 294—26)

This invention pertains to marine beacons, especially to those of the gas-burning type, and relates particularly to an implement for use in servicing such beacons.

In the patent to Connover, No. 1,623,464, dated April 5, 1927, there is disclosed an improved gas burner for use in such beacons, specifically a V-type burner having a separate pilot jet for each of the opposed burners. As described in said patent, to which reference may be had for additional details, the pilot jet orifices are formed in the wall of the transverse or horizontal portion of an inverted U-shaped pipe, the legs of said U-shaped pilot pipe being telescoped into parallel sockets in the burner base, and each communicating, when seated in its socket, with a source of pilot-flame gas.

The device thus described in said patent is very effective for its intended purpose and has been quite generally adopted. However, it does offer certain difficulties with respect to the servicing of the beacon. To insure dependable operation of such beacons, it is necessary, at regular intervals, to examine them and to clean the burner and adjacent parts. One step in such servicing of a burner of the type shown in the Connover patent is to pull the U-shaped pilot pipe up out of the burner to permit its passages and jet orifices to be thoroughly cleaned. However, the transverse portion of this pilot pipe is nested in the V-groove between the opposed burner members, and the dimensions of the parts are such that it is very difficult to seize with the fingers this part of the pilot pipe for withdrawing it from the burner. This difficulty is often increased by the fact that the legs of the U-shaped pipe may be corroded by the salt air and thus become very firmly fixed in their sockets. Moreover, if the burner is still operating when the servicer begins work, the parts are too hot to handle. Sometimes the servicer resorts to pliers for removing the U-shaped pilot pipe, but if real force be applied by means of such a tool, the pilot pipe may be permanently distorted so that it can not be returned to its operative position, or its jet orifices may be buried or thrown out of line. Thus, the use of such a tool is not to be recommended.

The principal object of the present invention is to provide an implement for use in servicing beacons of the kind referred to, and in particular an implement by means of which the U-shaped pilot pipe of a burner of the Connover type may readily be withdrawn (without danger of injury) from its sockets in the burner, even though the parts have become corroded or are hot.

A further object is to provide an implement of this kind which is simple, durable, inexpensive to make, of small dimensions so that it may be carried in the pocket, and which is so shaped as to apply the withdrawing force to the pilot pipe in a direction such that the pilot pipe does not tend to tip and bind.

Other and further objects and advantages of the invention will be pointed out in the following 10 more detailed description and by reference to the accompanying drawing in which:

Fig. 1 is a perspective, substantially to actual size, of the improved implement of the present invention;

15 Fig. 2 is a side elevation of a beacon burner showing the tool of the present invention applied to the pilot pipe in readiness for withdrawing the latter from the burner;

20 Fig. 3 is a front elevation of the parts shown in Fig. 2 with certain portions in vertical section; and

Fig. 4 is a view similar to Fig. 3 but showing the 25 pilot pipe as having been withdrawn from the burner proper by the operation of the implement.

Referring to the drawing, the numeral 1 designates the upper portion of the base of the beacon burner of the kind shown in the patent to Connover above referred to. Mounted on this base is the V-shaped burner comprising the upwardly and oppositely inclined arms 2 and 3 which have the jet apertures (not shown) in their upper, inner faces. The part 1 of the burner base is provided with vertical passages 4 (only one being shown) leading from the source of gas for actuating the pilot jets, and in axial alignment with these passages 4 the burner base is provided with vertically elongate sockets 5 in which are telescoped the lower end portions of the parallel tubular legs 6 of the inverted U-shaped 30 pilot pipe, said legs being integrally connected at their upper ends by the transverse or horizontal portion 7. From this horizontal portion project the pilot jet nipples 8 and 9, parallel, respectively, to the divergent burner members 2 and 3. These 35 jet nipples 8 and 9 receive pilot-flame gas from the tube 7 and direct it so as to ignite the gas issuing from the main burner arms 2 and 3. As suggested in the Connover patent, it is desirable to provide heat-dissipating means for the legs 6

40 of the U-shaped pilot pipe, and to this end shields or fins 10 and 11 of thin sheet metal are secured in any suitable way to the legs 6 of the pilot pipe, said shields or fins each having a pair of diverging wings whose inner edges are spaced a short 45 distance from the side walls of the burner mem- 50

bers 2 and 3. When the U-shaped pilot pipe is in operative position, with the lower ends of its legs 6 telescoped into the sockets in the burner base, the transverse portion 7 of the pilot pipe is located in the V-groove between the burner parts 2 and 3, while its opposite end portions are shielded by the upper parts of the heat dissipators 10 and 11. It is thus only at the central part of the pipe member 7 that the latter is accessible for effective seizure, and at this point the space between the jet members 8 and 9 and the burner members 2 and 3 is so small that it is quite difficult for the service man to seize the pilot pipe between his fingertips for removing it from the burner.

In accordance with the present invention, the improved implement of Fig. 1 is provided, such implement comprising an elongate head portion 12, which may be a piece of square bar stock, and which is shaped at its lower portion to provide a pair of parallel elongate members 13 and 13^a which terminate in upturned hook ends 14 and 14^a, thus providing the recesses 15 which are of such dimensions as to permit the pilot pipe member 7 to be received within them. Preferably, to facilitate engagement of the hook members with the pilot pipe, the extreme ends of the hook members are beveled as shown at 16. For manipulating the device, there is provided a handle, here shown as comprising an elongate cylindrical shank portion 17 which may be and preferably is integral with the head member 14, and which, at its upper end, is provided with a transverse finger-engaging bar 18 by means of which updrawing force may be effectively applied to the implement.

The legs 13 and 13^a are so laterally spaced that they may be disposed at opposite sides of the burner members 2 and 3, as shown in Fig. 3, and are of such transverse thickness as to permit them to be entered between the burner members 2 and 3 and the inner edges of the heat-dissipating members 10 and 11.

In using the device, the shank portion 17 of the handle is preferably held in an inclined position (inclining to the left with respect to its position shown in Fig. 2), and its hook portions are pushed down between the burner members 2 and 3 and the heat-dissipating members. The head is then moved laterally to bring the recess 15 into registry with the transverse member 7. The shank 17 may then be returned to the vertical

position shown in Figs. 2 and 3 and lifting force is applied to the bar 18. Since the hook members are disposed at opposite sides of the pilot jet nipples 8 and 9, and at substantially equal distances from the axes of the legs 6, the force thus applied is a straight uplifting force having no substantial component tending to tip the U-shaped pilot pipe and thus to bind it in its sockets, and there is no danger of damage to the pilot jet nipples. By the use of this implement, the pilot pipe may readily be removed even though hot or corroded and without danger of permanent injury either to the pilot pipe or to other parts of the burner.

While one desirable embodiment of the invention has been illustrated by way of example, it is to be understood that the invention is not necessarily limited to this precise arrangement but is to be regarded as broadly inclusive of any equivalent construction falling within the terms of the appended claim.

I claim:

An implement for use in servicing a gas-burning beacon of the kind having upwardly divergent burners, an inverted U-shaped pilot pipe having jet nipples in its horizontal portion whose axes are substantially parallel to those of the respective burners, the legs of the pilot pipe being telescopically fitted into sockets in the burner base, and a heat-dissipating shield secured to each of the parallel legs of the pilot pipe, each shield comprising diverging wings whose inner edges are spaced a short distance from the side walls of the burners, said implement comprising an integral length of square bar stock shaped to provide an elongate head having an integral upwardly extending elongate cylindrical shank portion, and a pair of hooks integral with and extending downwardly from the lower end of the head, said hooks being parallel and spaced apart horizontally a distance such as to receive the burners between them, the hooks being of such transverse thickness that each hook may be introduced between the burners and the inner edges of the adjacent heat-dissipating shield, respectively, the hooks being rigid and substantially parallel from their junction with the body of the head and having upwardly open recesses of such dimensions as to receive the transverse portion of the pilot pipe within them.

GEORGE F. STEWART.
